UNITED STATES PATENT OFFICE.

SWINFEN BRAMLEY-MOORE, OF WHITE PLAINS, NEW YORK, ASSIGNOR OF ONE-HALF
TO JOHN MCINTYRE, OF PORTOBELLO, MIDLOTHIAN, SCOTLAND.

CRUSHING, GRINDING, REFINING, AND MIXING MACHINE.

Application filed October 22, 1925. Serial No. 64,205.

The present invention relates to crushing, grinding, refining and mixing machines, and aims to provide improvements in the coating members having a rubbing or wiping contact when crushing, grinding, refining or mixing material between them.

The improvements may be used in various machines, being particularly intended for use in chocolate making machines, although the improvements may be used in machines for crushing, grinding, refining and mixing various materials.

Another object of the invention is the provision of rubbing or wiping contact means including rubbing or wiping members having rocking or oscillatory action as they move along a surface with which they are in contact.

A further object is the provision for mounting the rubbing or wiping members for rocking action.

A still further object is the provision of such a device wherein the rubbing or wiping members will not wear flat, said members having rounded surfaces which will wear away to maintain the surfaces curved or rounded.

It is also an object of the invention to provide the improvements aforesaid using a simple, practical and efficient construction.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

Figure 1 is a fragmentary side elevation of a crushing, grinding, refining or mixing machine embodying the improvements, portions being shown in section.

Fig. 2 is a section on the line 2—2 of Fig. 1.

Fig. 3 is a rear edge view of the parts shown in Fig. 2.

The improvements are illustrated as being embodied in a rotary machine comprising a cylinder or cylindrical casing 7, constituting the stator or stationary member, within which the rotor or rotary member is movable. However, the improvements may be used in other types of machines for which the improvements are suitable. For ex-

ample, the member 7 may be flat or of other form than as shown, the action of the rubbing or wiping members 8 against the member 7 being the same. However, for purpose of convenient description, the rotary motion will be referred to, without limitation thereto.

The rubbing or wiping members 8 are of barlike form and are disposed transversely of their path of movement along the inner or active surface of the cylinder or member 7, said surface being of stepped formation, so as to have the steps 9 of ratchet-like form. Each member or bar 8 is provided with a pair of longitudinal ribs 10 whose surfaces are convexed or rounded transversely thereof, and said rounded or curved surfaces of the bars 8 rub or wipe along the stepped surface of the member 7, to act upon the material between the members 7 and 8 for crushing, grinding, refining or mixing the material. The steps 9 of the member 7 are formed with small grooves 11 parallel with the steps, which have been found to facilitate the action on the material as the bars or members 8 move along the steps over said grooves.

The members or bars 8 are held yieldingly under spring pressure against the member 7, to obtain the desired pressure between the members 7 and 8, and the yielding action permits the members 8 to have rocking or oscillatory action when moving from each step 9 to the next, as will hereinafter more fully appear, in order to facilitate the grinding action as well as to cause the members 8 to wear down along curved surfaces.

As shown, the members 8 are arranged in groups, with two sets of members 8 in each group, and any suitable number of aligned members 8 in each set disposed end to end. Each member or bar 8 is provided at that side opposite to the ribs or rounded surfaces 10 with ears or lugs 12 through which front and rear rods 13 and 14 extend parallel with the member 8. A leaf spring 15 is provided at its free end with a sleeve 16 loosely embracing the rod 13 intermediate the ends of the member 8, and other leaf springs 17 have sleeves 18 at their free ends loosely embracing the rod 14. As shown, the spring 15 is broad, while the springs 17 are narrow, with the springs 17 arranged adjacent the ends of the member 8, and the spring 15 between the springs 17. Thus,

- each member or bar 8 has a double hinge connection with the leaf springs 15 and 17 thereof, permitting the rocking or oscillatory movement of the member 8 about the spaced axes of the rods 13 and 14. The springs 15 and 17 have their sleeves 16 and 18, respectively, located between the ears or lugs 12, thereby holding the member 8 and springs assembled.
- 10 For each group of members 8 there is provided a carrier comprising bars 20, 21 and 22 between which the leaf springs are clamped and secured, so that said springs are trailed from said bars to drag the members 8 along the member 7. The leaf springs 15 and 17 of one set of each group are longer than the springs of the other set of members 8, to space the two sets of members 8 apart, and the rear members 8 of the group are of greater height than the members 8 of the front set, whereby the two sets of members may be spaced apart longitudinally of the line of movement thereof. The springs 15 and 17 of the front member 8 of each group are clamped between the bars 20 and 21, while the spring of the rear members 8 of the group are clamped between the bars 21 and 22.
- As shown, the bars 20, 21, 22 of each group of members 8 are riveted or otherwise secured together, and are carried by an arm 23. Said arms 23 are pivoted, as at 24, to a wheel or rotary member 25, to enable the arms 23 to be adjusted about the pivots 24 in order to regulate the pressure with which the springs 15 and 17 press the members 8 against the member 7. The mounting and adjustment of the arms 23 may be the same as disclosed in the copending application of John McIntyre, Serial No. 693,686, filed February 18, 1924. Thus, a ring 26 is mounted for turning movement on the wheel 25, and has slots 27 engaged by pins or studs 28 carried by the arms 23, in order that the turning adjustment of the ring 26 on the wheel 25 will swing the arms 23. By swinging the arms rearwardly the pressure of the springs 15 and 17 is relieved, whereas when the arms are swung forwardly with reference to the direction of rotation, the springs are flexed or bowed so as to increase the pressure. One or more of the arms 23 may have the arms 29 with which suitable adjusting means 30 is connected, in order that the ring 26 may be adjusted on the wheel 25.
- In operation, the rubbing or wiping members 8 are moved along the members 7, the motion being circular in the machine as shown, and the springs 15 and 17 press said members 8 with the desired pressure against the member 7 to obtain the grinding, refining, crushing or mixing action. The small grooves 11 facilitate the action by reducing the tendency for the material to slide along the member 7 with the members 8, so that the members 8 will pass across the particles for crushing or grinding same. As the front rib 10 of each member 8 passes from one step 9 to the next step, the member 8 rocks forwardly on the rear rib 10, and then as the rear rib passes to the lastnamed step, the member 8 rocks rearwardly on the front rib 10. In this way, the members 8 have rocking or oscillatory motions forwardly and rearwardly on the rear and front ribs 10, respectively, as said members move along the steps 9 of the member 7. This assists in the grinding or crushing action, as well as preventing the members 8 from wearing down flat. To the contrary, the ribs or curved surfaces 10 will wear down along curved lines to maintain the convex curvature of said ribs, and thereby maintain the advantageous grinding or crushing action that the curved ribs or surfaces 10 possess. The springs 15 and 17 enable the members 8 to rock or oscillate forwardly and rearwardly a limited amount, the springs 15 holding the front ribs 10 against the member 7, while the springs 17 hold the rear ribs 10 against said member 7. The springs 15 and 17 are yieldable, so that either the front or the rear ribs 10 may move away from the member 7 to a limited extent.
- The rocking motion of the members 8 will not only increase the life thereof, but will also decrease the time necessary for accomplishing the work to be performed.
- Having thus described the invention, what is claimed as new is:
1. In a device of the character described, a wiping member having a rounded surface to move along and rock against a coacting surface, a carrier movable along said coacting surface, and spring means connecting said member and carrier to press the member against said coacting surface and constructed and arranged to permit said member to have rocking movement on the rounded surface thereof.
  2. In a device of the character described, a wiping member having a rounded surface to move along and rock against said coacting surface, a carrier movable along said coacting surface, and spring means carried by said carrier and having front and rear hinge connections with said member to press said member against said coacting surface and permit said member to have rocking movement on said rounded surface thereof.
  3. In a device of the character described, a member having a stepped surface, a wiping member having a rounded surface to move along and rock against said stepped surface, a carrier movable along said stepped surface, and spring means connecting said carrier and member for pressing said member against said stepped surface and

- constructed and arranged to permit said member to rock on said rounded surface thereof.
4. In a device of the character described, 5 a member having a stepped surface, a wiping member having a rounded surface to move along and rock against said stepped surface, a carrier movable along said stepped surface, and spring means connected to said 10 carrier and having front and rear hinge connections with said member to press said member against said stepped surface and permit said member to rock on said rounded surface thereof.
- 15 5. In a device of the character described, a carrier movable along the surface of a member, a wiping member having a rounded surface to move along and rock against the first named surface, and leaf springs carried by 20 said carrier and having front and rear hinge connections with said member to press said member against the firstnamed surface and to permit said member to have rocking movement on said rounded surface thereof.
- 25 6. In a device of the character described, a member having a stepped surface, a carrier movable along said surface, a wiping member having a rounded surface to contact with said stepped surface and rock thereagainst, 30 and leaf springs secured to the carrier and having front and rear hinge connections with said member for pressing said member against said stepped surface and permitting said member to rock on the rounded surface 35 thereof.
7. In a device of the character described, a wiping member having front and rear rounded surfaces to move along a coacting surface, and means mounting said member for movement along said coacting surface, and for rocking movement on either of said rounded surfaces while moving along and in contact with said coacting surface.
8. In a device of the character described, 45 a wiping member having front and rear rounded surfaces to move along a coacting surface, and spring means mounting said member for movement along said coacting surface under pressure thereagainst and for 50 rocking movement on either of said rounded surfaces while moving along and in contact with said coacting surface.
9. In a device of the character described, 55 a wiping member having front and rear rounded surfaces to move along a coacting surface, and leaf springs connected to said member for moving it along said coacting surface and pressing said member against said coacting surface, the connection between 60 said member and springs being such that said member is capable of rocking on either rounded surface while moving along and in contact with said coacting surface.
10. In a device of the character described, 65 a carrier movable along a surface, leaf springs carried by said carrier, and a member having different hinge joint connections with said leaf springs to be pressed against said surface, said member having front and rear rounded surfaces to bear against the 70 firstnamed surface, and the hinge joint connections being so arranged as to permit said member to rock on either rounded surface while moving along and in contact with the firstnamed surface.
11. In a device of the character described, 75 a wiping member having front and rear rounded surfaces to move along a coacting surface, and spring means mounting said member for movement along said coacting surface under pressure thereagainst and having front and rear hinge joint connections with said member, said member having front and rear rounded surfaces corresponding with said hinge joint connections to contact with said coacting surface.
12. In a device of the character described, 80 a carrier movable along a surface, a wiping member having front and rear rounded surfaces to bear against the firstnamed surface, front and rear hinge rods carried by said member corresponding with said rounded surfaces, and leaf springs carried by said carrier and engaging said rods.
13. In a device of the character described, 85 a carrier movable along a surface, a wiping member having front and rear rounded surfaces to move along the firstnamed surface and having lugs opposite to said rounded surfaces, front and rear hinge rods extending through said lugs and corresponding with said rounded surfaces, and leaf springs carried by said carrier and having sleeves at their free ends embracing said rods between 90 said lugs.
14. In a device of the character described, 95 a member having a stepped surface, a wiping member having front and rear rounded surfaces to move along said stepped surface, and means mounting said member for movement along said stepped surface and for rocking movement on either rounded surface while moving along and in contact with said stepped surface.
15. In a device of the character described, 100 a member having a stepped surface, a wiping member having front and rear rounded surfaces to move along said stepped surface, and spring means mounting said member for movement along said stepped surface and having front and rear hinge joint connections with said member corresponding with said rounded surfaces to enable said member to rock on either of said rounded surfaces while moving along and in contact with said 105 stepped surface.
- 110 In testimony whereof I hereunto affix my signature.

SWINFEN BRAMLEY-MOORE.
